UNITED STATES PATENT OFFICE.

MAX MUNZESHEIMER, OF DALLAS, TEXAS.

DESIGN FOR A CORNER-WEIGHT FOR RUGS.

SPECIFICATION forming part of Design No. 33,995, dated January 29, 1901.

Application filed December 24, 1900. Serial No. 40,987. Term of patent 14 years.

To all whom it may concern:

Be it known that I, MAX MUNZESHEIMER, a citizen of the United States, residing at Dallas, in the county of Dallas and State of Texas, have invented and produced a new and useful Design for Corner-Weights for Rugs, of which the following is a specification.

My invention relates to new and useful designs for corner-weights for rugs, of which the following is a specification, reference being had to the accompanying drawings, forming a part thereof, in which—

Figure 1 is a perspective of my new design. Fig. 2 is a plan view of the same.

Like characters of reference designate like parts in both views of the drawings.

My weight has two parallel faces 1, each of which has two straight sides equal in length and perpendicular to one another and a third side 3 consisting of a double reverse curve formed of three circular arcs tangent to each other at the points of reversal. The faces 1

are separated from each other about one-half inch and are connected by straight plain sides 4; but their corners 5, formed at the lines of junction, are slightly rounded.

The leading or material feature of my design consists of the parallel faces connected at their edges and having two equal straight sides at right angles to each other and a third side consisting of a double reversed curve.

Having described my invention, what I claim as new, and desire to secure by Letters Patent, is—

The design for a corner-weight for rugs, substantially as herein shown and described.

In testimony whereof I have hereunto set my hand in presence of two subscribing witnesses.

MAX MUNZESHEIMER
